UNITED STATES PATENT OFFICE.

THOMAS R. BROWN, OF NEW YORK, N. Y., ASSIGNOR TO AMERICAN CAR & FOUNDRY COMPANY, OF ST. LOUIS, MISSOURI, A CORPORATION OF NEW JERSEY.

METALLIC-CAR CONSTRUCTION.

No. 799,969.

Specification of Letters Patent.

Patented Sept. 19, 1905.

Application filed May 20, 1905. Serial No. 261,452.

To all whom it may concern:

Be it known that I, THOMAS R. BROWN, a citizen of the United States, residing in the city, county, and State of New York, have invented a certain new and useful Improvement 5 in Metallic-Car Construction, of which the following is a full, clear, and exact description, such as will enable others skilled in the art to which it appertains to make and use the same, reference being had to the accompanying 10 drawings, forming part of this specification, in which—

Figure 1 is a cross-sectional view through a car constructed in accordance with my invention. Fig. 2 is a sectional view on the line 2 2 of Fig. 1. Fig. 3 is a sectional view on the line 3 3 of Fig. 1, and Fig. 4 is a perspective view showing the construction of the gusset.

20 This invention relates to metallic cars, and particularly to freight-cars of the type in which is employed a hopper-bottom.

The object of the invention is to provide means for bracing the entire car-body and to 25 do this with a car of minimum weight.

Another object is to reinforce the sides of the car, so as to stiffen them and assist in resisting the strains to which the sides would be subjected under load, and a further object 30 of the invention is to assist in tying in the sides to the underframe.

Other objects and advantages, as well as the novel details of construction of this invention, will be more specifically referred to 35 hereinafter, it being understood that changes in the form, proportion, and minor details of construction may be resorted to without departing from the spirit of my invention or sacrificing any of the advantages thereof.

40 Referring now to the drawings, 1 designates the center sill, having two members of channel form with outwardly-disposed flanges, the cross-bearers 2 being illustrated as comprising channels secured at their inner ends to 45 the webs of the center-sill channels by angle-plates 3, and these channels are secured to the plate-girder sides 4 by angle-plates 5. The upper edges of the plate-girder sides have integral outwardly-disposed edges comprising flanges 6. Resting on the top of these outwardly-disposed edges 6 are the webs of channels 7, which webs are riveted to the flanges 6, and the flanges of the channels 7 depend

from the webs. The plate-girder sides 4 extend below the cross-bearers 2 and below the 55 center sills and have outwardly-projecting flanges 8, which serve as the bottom chords of the plate-girder sides, the upper chords being the channels 7 in combination with the outwardly-turned flanges 6.

60 9 designates a cross-bearer arranged intermediate the ends of the car and positioned between the twin hoppers, such as are used on a common type of twin-hopper car, and this cross-bearer 9 comprises a construction 65 in the form of an I in cross-section, which in practice will preferably consist of two channels 10 and 11, with their webs arranged back to back. The ends of the channels 10 and 11 are secured to the respective sides of the car 70 by angle-plates 13. The lower flanges of the channels are shown as depending below the bottoms of the sides and rest on bracket-plates 14, which are secured to the sides of the car and have their ends provided with in-turned flanges 15, which are secured to said bottom flanges.

75 A gusset-plate 16 is arranged at the center of the car and provided at one edge with oppositely-disposed flanges 17 and 18, which are 80 secured to the plate-girder side. The flange 17 forms a part of the gusset, while the flange 18 is a flange of an angle 19 riveted to the gusset and to the plate-girder side. The flanges 17 and 18 extend down to the floor, 85 where they terminate. The gusset continues through the floor and is secured to the web of the channel cross-bearer 2 and is interposed between the webs 10 and 11 of the cross-bearer 9, so that the rivets 20 secure the channels 10 and 11 together and at the same time 90 secure the lower portion of the gusset there-between.

95 At the other portions of the car the gussets 16^a extend only to the cross-bearer or floor-support, to which they are riveted by rivets passing through the webs of said floor-support. The floor-sheet 21 extends over the bottom of the car and is fastened to the floor-supports in any suitable manner, and the 100 edges of the floor-sheet at the sides are up-turned and fastened to the plate-girder sides of the car. A cover-plate 22 is riveted to the top flanges of the channel center-sill members by rivets, which pass through the floor-sheet 105 and through the top flanges of said channels.

On the outside of the car are stakes or posts 23, which are of pressed shapes and have oppositely-disposed flanges 24 and 25, which are riveted to the sides of the car by rivets which 5 secure the flanges of the gusset to the plate-girder sides, and in order to additionally strengthen the car adjacent the stakes inserted plates 26 and 27 may be used, which plates are interposed between the flanges of the 10 gussets and the car sides and between the flanges of the stakes and the car sides. The upper ends of the stakes have flat extensions 15 28, with outturned extremities 29, which are riveted beneath the outwardly-disposed flanges 6 of the sides, so that the whole structure will be braced against the strains to which a car of this type will be subjected.

In Fig. 4 I have illustrated a gusset 30 in most respects similar to the gusset 16^a, but 20 in this form the base of the gusset or bottom thereof is provided with an outturned flange 31, which is riveted to the floor, and the hypotenuse of the angle of which the gusset consists is provided with a flange 32, integral 25 therewith so as to protect the edge of the gusset against injury from contact with the load. This flange 32 will prevent injury to the gusset under certain conditions—as, for example, when pig-iron ingots are thrown 30 into the car.

33 designates one end of the car, which may be secured to the underframing and plate-girder sides in any preferred manner, the ends of the car being preferably provided with 35 channel upper chords and stakes.

From the foregoing it will be seen that a car constructed in accordance with the one just described will possess a maximum strength and will be capable of resisting all the strains to 40 which it would ordinarily be subjected, and that by providing the gussets and securing them to the underframing the rivets which fasten the gussets to the sides will be under tension, and thus have a tendency to resist any 45 bulging of the sides from any cause.

Having thus described the invention, what is claimed as new, and desired to be secured by Letters Patent, is—

1. In a metallic car, the combination of 50 plate-girder sides, floor-supports connected to the center sill and sides and flush with the tops of the center-sill members, floor-sheets connected to all of said parts, and gussets having oppositely-disposed flanges connected to the sides of the car, one flange of which is a part of an angle and the other flange being integral with the gusset, the bottom portions of 55 said gussets being connected to the floor-supports; substantially as described.

2. In a metallic car, the combination with 60 a center sill, cross-bearers carried by said center sill, plate-girder sides connected to the cross-bearers, gussets connected to the cross-bearers and sides, the parts of the gussets adjacent the sides having right-angularly bent

edges comprising flanges secured to said sides, and angle members carried by the gussets and alining with the flanges and also secured to said sides; substantially as described.

3. In a metallic car, the combination with 70 a center sill, of plate-girder sides, gussets connected to said plate-girder sides and floors of the cars, each of said gussets having one edge bent to form a flange which is secured to the sides, and an angle secured to each gusset and 75 alining with the bent edge and also secured to a car side; substantially as described.

4. In a metallic car, the combination with 80 a center sill, floor-supports and plate-girder sides, of a gusset connected to the plate-girder 85 sides and floor-supports and extending below the same, and a cross-bearer below the center sill, said cross-bearer being secured to the gussets; substantially as described.

5. In a metallic car, the combination with 85 a center sill and plate-girder sides, of floor-supports connected to the center sill and plate-girder sides, the bottoms of the floor-supports being above the lower portions of the center sill, and the plate-girder sides extending below the center sill, gussets secured to the plate-girder sides and extending below the center 90 sill, and a cross-bearer below the center sill, and connected to the gusset; substantially as described.

6. In a metallic car, the combination with 95 plate-girder sides, a center sill, and floor-supports extending from the center sill to the plate-girder sides, of gussets connected to the plate-girder sides and extending below the 100 floor-supports to which they are secured, and a cross-bearer connected to the respective gussets and comprising channels whose webs are arranged back to back and between which a portion of each gusset is riveted; substantially as described.

7. In a metallic car, the combination with 105 a center sill and car sides, of floor-supports connected to the car sides and center sill, a gusset connected to the side and floor-supports 110 and flanged along its free inclined edge; substantially as described.

8. In a metallic car, the combination with 115 a center sill and plate-girder sides, of floor-supports connected to the center sill and plate-girder sides, gussets arranged at the center of the car and connected to the plate-girder sides, portions of said gussets extending below the floor-supports, a cross-bearer beneath the center sill and extending from car side to 120 car side, said cross-bearer being secured to the gussets, and gussets between the center and ends of the car which are secured to the plate-girder sides and the floor-supports only; substantially as described.

9. In a metallic car, the combination with 125 a center sill and plate-girder sides extending below the center sill, floor-supports connected to the plate-girder sides and center sill, a gusset connected to the floor-support and extend-

ing below the center sill, a cross-bearer extending from car side to car side and connected to the gussets, and bracket-plates secured to the sides and having flanged portions 5 engaging the cross-bearer; substantially as described.

In testimony whereof I hereunto affix my

signature, in the presence of two witnesses, this 15th day of May, 1905.

THOMAS R. BROWN.
